UNITED STATES PATENT OFFICE.

GEORGE F. TROTTER, OF ST. LOUIS, MISSOURI, ASSIGNOR TO TRIPLEX VIBRATOR COMPANY, OF ST. LOUIS, MISSOURI, A CORPORATION OF ARIZONA TERRITORY.

MASSAGE-MACHINE.

No. 837,979.

Specification of Letters Patent.

Patented Dec. 11, 1906.

Application filed May 21, 1906. Serial No. 317,929.

To all whom it may concern:

Be it known that I, GEORGE F. TROTTER, a citizen of the United States, residing at St. Louis, Missouri, have invented a certain new and useful Improvement in Massage - Machines, of which the following is a full, clear, and exact description, such as will enable others skilled in the art to which it appertains to make and use the same, reference being had to the accompanying drawings, forming part of this specification, in which—

Figure 1 is a side elevation of a massage-machine embodying the features of my invention, portions of the motor-casing and support being broken away to more clearly show the construction of parts of the machine. Fig. 2 is an end view of the machine, taken on the line 2-2 of Fig. 1. Fig. 3 is a view similar to Fig. 1, showing the applicator-carrying member in the position it occupies at the beginning of its stroke. Fig. 4 is an end view showing in broken lines the various positions of the applicator when a combined gyratory and oscillatory movement is being imparted to it, and Fig. 5 is an end view showing in broken lines the different positions of the applicator when a strictly vibratory movement is being imparted to it.

This invention relates to massage - machines.

One object of my invention is to provide a massage-machine having means for imparting either a gyratory or an oscillatory motion to the massaging instrument or "applicator," as it is commonly called.

Another object of my invention is to provide a massage-machine having a removable applicator-carrying member which can be replaced by a new one when it becomes worn out, and thus enable the machine to be used for an extended period.

Another object of my invention is to provide a massage-machine comprising a motor and an applicator and means for imparting a compound movement to the applicator, so that the patient being operated on will receive a pounding and a rubbing action simultaneously.

Another object of my invention is to provide means for varying the degree of movement which is imparted to the applicator while the machine is still in operation, thus permitting the machine to be used for very

gentle massaging or for vigorous massaging without stopping the machine and readjusting it.

Another object of my invention is to provide a novel means for lubricating the connection between the armature-shaft and the applicator-carrying member which it actuates; and still another object of my invention is to provide a machine in which the applicator is perfectly balanced so that the machine will not vibrate.

Other desirable features of my invention will be hereinafter pointed out.

Referring to the drawings, which represent the preferred form of my invention, I designates a shell or casing having a motor mounted therein, said casing being provided with a handle 2, through which the wires 3 and 4 extend to the motor. A tubular support 5 is connected to the casing 1, and removably mounted in the outer end of said tubular support is the member which carries the massaging instrument or applicator 6. This applicator-carrying member consists of a cylindrical bearing 7, which fits into the end of the tubular support 5 and is held in operative position by a screw 8 threaded therein and extending through an elongated slot in the tubular support, a clamp 9 being interposed between the head of said screw and the outer surface of the tubular support, as shown in Fig. 1 of the drawings. The bearing 7 is provided with a central bore or slot 10, which extends to the periphery of said bearing, as shown in Fig. 2, and the device which carries the applicator 6 is located in said slot. Said device preferably consists of two blocks 11 and 12, the block 11 being pivotally connected to the bearing 7 by a pin 13, arranged at one side of the longitudinal axis of said bearing, and the block 12, which has a shank 14, that is connected to the armature-shaft 15, being pivotally connected to the block 11 by a pin 16, extending at right angles to the pin 13, so that the applicator is fastened to the armature-shaft by a universal connection of simple construction which can be manufactured at a small cost.

The armature-shaft of the motor is provided with an extension 17, which projects at an angle to said shaft and acts as a crank-pin to impart a rotary movement to the shank 14 of the block 12, and accordingly transmit

a gyratory motion to the applicator 6 when it is connected to the block 12, as indicated by the arrows 18 in Fig. 2. An oscillating motion is imparted to the applicator simultaneously with the gyratory motion, so that said applicator will pound, as well as rub, the patient being operated on, thereby producing a massage which is greatly superior to any produced by the machines heretofore in use, which were capable of imparting only a rubbing action. This oscillating motion that is imparted to the applicator simultaneously with the gyratory motion is effected by pivoting the block 11 at one side of the longitudinal axis of the bearing 7, so that said applicator will swing about the pin 13 as a fulcrum, as shown in Fig. 3, which in full lines shows the applicator in the positions it occupies at the beginning of its stroke and in broken lines the position it occupies at the end of its stroke. Fig. 4 shows in broken lines the various positions which the applicator 6 assumes when a combined gyratory and oscillatory movement is being imparted to it. The end of the shank 14 is provided with an enlarged hollow portion 19, having a closed end provided with an opening for receiving the extension 17 on the end of the armature-shaft to connect said shank and shaft together. If desired, the applicator-carrying member can be moved inwardly to cause said extension to project farther into the enlarged hollow portion of the shank, thus not imparting as great a degree of movement to said shank and to the applicator as when the extreme outer end of said extension engages the closed end of the shank. This is a very desirable feature of my invention, as it enables the machine to be used for massaging very gently or for massaging vigorously without stopping the machine to readjust any of the parts, it being simply necessary for the operator to loosen the screw 8 and move it to change the position of the bearing 7. Furthermore, if desired, the operation of the applicator can be discontinued, while the motor continues in operation if the bearing 7 is moved inwardly far enough to cause the straight portion of the extension 17 to engage the closed end of the enlarged portion of the shank 14, this straight portion of course being located at the center of the armature-shaft. For keeping the connection between the shank of the applicator and the armature-shaft thoroughly lubricated the enlarged portion 19 of the shank is packed with felt soaked with oil.

For some classes of work—such, for example, as when a very vigorous massage is desired—a strictly vibratory or oscillatory motion of the applicator is more effective than a combined gyratory and oscillatory motion, and for producing this oscillatory motion the applicator is mounted in the block 11, which is pivoted to the bearing 7 at 13, and accord-

ingly has only a rocking movement imparted thereto, as indicated by the arrows 18^a in Fig. 2 or in Fig. 5, which shows in broken lines the various positions which the applicator assumes when it is mounted in the block 11.

By examining Fig. 1 it will be seen that the fulcrum or point about which the applicator moves is located approximately midway the end of the applicator and the end of the shank 14, where it is connected to the armature-shaft. By constructing the machine in this manner the applicator is perfectly balanced, so that there is practically no vibration to the machine, and accordingly the operator, who holds the machine in his hand, can handle the machine more accurately. The applicator-carrying member is the part which receives the greatest wear, and accordingly wears out quicker than the motor and the other parts of the machine; but as said member is removable it can be replaced by a new one at a small cost, and thus enable the machine to be used for an extended period. It will of course be understood that the particular kind of applicator that is used in the machine is immaterial, as different applicators are used for different classes of work.

Having thus described my invention, what I claim as new, and desire to secure by Letters Patent, is—

1. In a machine of the class described, a motor, a pivotally-mounted applicator-carrying device eccentrically connected to the armature-shaft of said motor, and a pivotally-mounted member carrying said device and having its pivot arranged at approximately a right angle to the pivot of said device and adjacent one end thereof; substantially as described.

2. In a machine of the class described, a motor, an oscillating member adapted to have an applicator connected thereto, a device connected to said member by a pivot extending at approximately right angles to the axis on which said member oscillates, said device also being adapted to have an applicator connected thereto, and a shank on said device eccentrically connected to the armature-shaft of the motor; substantially as described.

3. In a machine of the class described, a motor having an armature-shaft provided with a crank-pin, a pivotally-mounted applicator-carrier having a shank provided with an enlarged hollow end which is packed with oil-saturated felt, and an end wall closing said hollow portion and provided with an opening to receive the crank-pin on the armature-shaft; substantially as described.

4. In a machine of the class described, a motor, a casing therefor, a tubular support connected to said casing, a cylindrical bearing telescoped in said support, a clamp-screw carried by said bearing and extending

through an elongated slot in the support, a clamping device arranged between the outer surface of the support and the head of the screw, and an applicator-carrying member fulcrumed in said bearing and eccentrically connected to the armature-shaft of the motor; substantially as described.

5. A device of the character described, comprising a motor mounted in a casing, a bearing mounted in a support on said casing, a block pivotally connected to said bearing at one side of the longitudinal axis thereof, and

an applicator-carrying member eccentrically connected to the armature-shaft of the motor and pivoted to said block by a pin which extends at approximately right angles to the pivot of said block; substantially as described.

10 In testimony whereof I hereunto affix my signature, in the presence of two witnesses, this 17th day of May, 1906.

GEORGE F. TROTTER.
